UNITED STATES PATENT OFFICE.

ADOLF GOTTLIEB, OF BRUNN, CZECHOSLOVAKIA.

HANGER STRAP.

Application filed October 15, 1923. Serial No. 668,742.

To all whom it may concern:

Be it known that I, ADOLF GOTTLIEB, a citizen of the Czechoslovakian Republic, and residing at V Hlinkac 146, Brunn, 5 Moravia, Czechoslovakia, have invented certain new and useful Improvements in and Relating to Hanger Straps, of which the following is a specification.

It has already been proposed to construct 10 the upper part above the grip of hanger devices for passengers in tram cars and the like so as to act as a carrier for advertising matter. Hitherto two groups of such hanger devices have been differentiated which 15 however are neither as simple as such devices should be nor display the advertising matter to the best advantage, owing to space for this purpose being insufficient. One of these two groups of hanger devices uses a definite 20 frame-like structure, which is suspended from the common supporting bar of the tram car and to the lower part of which a gripping part is attached. These arrangements have the disadvantage that they are 25 complicated and exclude the use of the usual band-shaped material for making such hanger straps. It has also been proposed and such constructions form the second of 30 the groups of hanger straps with an advertising device referred to, to make the band used for the hanger strap considerably wider at one part and to use this part either directly as a display board or indirectly as 35 the back of a frame, into which the advertising cards or the like are slipped. It has further been proposed to draw the band-shaped parts of the hanger strap through 40 strap buckles of flat frames, which rest against the band of the hanger strap and into the opening of which the advertising cards are slipped.

This last named group of hanger straps could never be of any practical importance as the size of the said band part or frame in 45 the plane at right angles to the plane of the loop of the strap, i. e. in the breadth direction of the band is very limited, since advertising boards projecting to such an extent beyond the width of the band as would 50 give them practical importance could not be used for aesthetic reasons or reasons of safety.

To overcome these drawbacks is the object of the present invention, according to which

the problem which has never been solved in 55 a practical manner of combining advertising devices with hanger straps for passengers, is now solved by the advertising plates being placed transversely of the open loops. Hence the advertising plates lie parallel to 60 the plane passing through the open loop of the hanger, so that without extending beyond the loop a considerably greater span than was hitherto the case is available for the advertising plates and a practical solution of the whole of the problem may be said to have been found.

In the accompanying drawing a constructional form of such a hanger strap is 65 shown,

Fig. 1 being a side view partly in section and

Fig. 2 a cross-section.

The lower part of grip of the hanger strap 1 may be provided with a cover 2 preferably 75 of enamelled sheet metal.

According to the invention the advertising plates are to fill transversely the opening of the hanger strap, which is open or held open, above the grip part. In a simple 80 constructional form the principal advertising plates form indirectly or directly the walls lying parallel to the plane, in which the open loop lies, of a casing, through which the band-shaped parts of the hanger 85 are drawn and rests in any suitable manner on the said bands. The frame-shaped casing 4 is further provided with transverse bars 5, which are held between the broader side walls of the casing and together with the narrow sides of the casing 90 form as it were openings bounded on all sides, through which the band-shaped parts of the hanger are drawn, so as to keep the latter open. The casing 4 rests for instance 95 on small plates 3, through which the parts 1 of the hanger-strap and which themselves rest on the edge of the cover 2. The advertising matter is stencilled either directly on the outer surfaces of the side walls of the 100 casing 4 or advertising plates are inserted in suitable guides on the side walls of the casing 4.

What I claim is:—

1. A hanger strap for the use of passengers in cars having in combination with an open strap having a grip part and a single loop for suspending it from a supporting

rod, means for holding the strap open and advertising plates transversely filling the open part in the strap above the grip.

2. A hanger strap for the use of passengers in cars having in combination with a strap having a grip part, means for holding the strap open, and a casing transversely filling the open part in the strap and having walls used for advertising matter above the grip, the strap passing through said casing, and the casing being held detachably on the strap.

3. A hanger strap, as claimed in claim 2,

and in which the means for keeping the strap open consists of transverse bars secured to the casing.

4. A hanger-strap, as claimed in claim 2, and having detachable small plates above the grip serving as a rest for the casing.

In testimony whereof I have signed my name to this specification.

ADOLF GOTTLIEB.
